(57) **CLAIM**

I claim the ornamental design for a barrier panel, as shown and described.

DESCRIPTION

FIG. 1 is a front perspective view of a barrier panel showing my new design.

FIG. 2 is a front elevational view of the barrier panel.

FIG. 3 is a left side elevational view of the barrier panel.

FIG. 4 is a right side elevational view of the barrier panel; and,

FIG. 5 is a plan view of the barrier panel.
